ELECTROHYDRAULIC ACTUATOR

Howard G. Farley, Detroit, Mich., assignor to Guerin Engineering, Inc., Ferndale, Mich., a corporation of Michigan

Filed May 24, 1962, Ser. No. 197,449
20 Claims. (Cl. 290—1)

This invention relates to power transmission and is particularly adaptable to those of the type comprising two or more fluid pressure energy translating devices, one of which may function as a pump and another as a fluid motor.

More particularly, this invention relates to electrically reproducing and recording the relative motion of a piston or the like and a cylinder, which motion produces a variable voltage or amperage output.

This invention further relates to an electro-fluid actuator which emits an electrical signal that is proportional to an increment of stroke. The generated signal has a wide range and is of an amplitude that readings or recordings can be taken directly from the cylinder lead.

One form of the electro-fluid actuator just mentioned consists of a cylinder and piston device in which a transducer assembly is mounted on the same axis and integral with the piston of said device. An elongated stylus is mounted in the cylinder along the longitudinal axis thereof and is provided with a taper on one side thereof. By suitable means the constantly varying cross sectional area of the stylus or the effective depth of the stylus is transmitted to the transducer so that a proportionate output signal is generated for each increment of stroke.

The output signal is properly amplified and delineated through and out of the cylinder by means of a cable around which an elastic tube or shroud is coiled for providing protection for the cable. The output signal thus generated is available to perform any task of control or readout that may be required. As an example, the actuator can be used as a remote control device for operating levers, chutes, rolls, dampers, and other mechanical devices. When the actuator is used as a position servo mechanism, the output can be applied directly to the compensation network or amplifier. When used as a position servo mechanism incorporating one or more of the actuators, the system will exactly duplicate manipulations repetitively on command after first being led through the given manipulations and the signal "memorized" on attendant equipment.

The present invention is adapted to be operated independently of the pressure of fluid acting in the cylinder and is characterized by its unique arrangement which provides a simplified, low cost structure, having certain advantages contributing to efficiency, reliability and long life, as well as ease of maintenance.

As previously mentioned, the actuator of the present invention may be utilized in many different applications. One example of an application is in conjunction with an industrial type of furnace wherein it is desirable to move the charge into the furnace a predetermined distance. In such a case, it is not easy to determine the position of the charge in the furnace due to the extreme heat and excessive temperature in the furnace. With the proposed application, the piston rod is connected to the movable charging mechanism of the furnace. The relative motion of the piston and the cylinder will in turn produce a change in mechanical energy of the actuating or follower arm, which change will move the core of the transducer in a direction to produce a corresponding electrical energy change in the transducer. A meter is connected to the transducer and calibrated to read in feet or inches so that a change in the electrical energy in the transducer deflects

2

the needle of the meter a predetermined distance. The meter would indicate the exact position of the charge in the furnace.

In addition, this invention is particularly characterized by its inherent versatility and high performance which makes it suitable for automation where the output of the device is fed to recorders, data processing and analyst equipment, as well as automatic process systems and permanently electrically recorded on tape. The tape in turn is utilized subsequently to obtain the exact sequence of mechanical motion from the actuating device as is electrically recorded on the tape.

It is an object of the present invention to provide a cylinder and piston device or the like which emits an electrical signal that is proportional to an increment of stroke.

Another object of the present invention is to provide an actuating device which includes an electro-fluid actuator having a transducer assembly integrally mounted within the cylinder of the actuator, thus providing flexibility of mounting, minimal design clearance, freedom of motion, and compounded angular movements.

Another object of the present invention is to provide an electro-fluid actuator wherein the transducer assembly is mounted on the same axis and integral with the piston of the cylinder.

A further object of the present invention is to provide an actuator comprising a tubular housing member, a wall member in said housing member, a linear movement camming action stylus in said housing member and fixedly mounted with respect to one of said members, and electro-mechanical transducer means carried by the other of said members and including movable follower means in contact with said stylus, said transducer means being effective to convert the relative displacement between said members as indicated by the movement of said follower means into an equivalent electrical energy change.

A still further object of the present invention is to provide an actuator of the aforementioned type wherein the housing member and the wall member are in the form of a cylinder and piston respectively.

Another object of the present invention is to provide an actuator of the aforementioned type wherein the stylus is fixed to the housing member and the transducer means is carried by the wall member.

Still another object of the present invention is to provide an actuator of the aforementioned type wherein the stylus and the housing member are elongated and the stylus has substantially the same longitudinal axis as the housing member.

A further object of the present invention is to provide an actuator of the aforementioned type wherein the stylus is elongated and the electro-mechanical transducer means has substantially the same axis as the stylus.

A still further object of the present invention is to provide an actuator of the aforementioned type wherein means are provided for aligning the axis of the electro-mechanical transducer means with the longitudinal axis of the stylus.

Another object of the present invention is to provide an actuator of the aforementioned type wherein the side of the stylus in contact with the follower means is tapered and the side directly opposite the tapered side is substantially straight.

Still another object of the present invention is to provide an actuator of the aforementioned type wherein the length of the taper on the stylus is substantially equal to the maximum linear displacement between the wall member and the housing member.

A further object of the present invention is to provide an actuator of the aforementioned type wherein means

are provided for connecting opposite sides of the wall member to a source of actuating fluid.

A still further object of the present invention is to provide an actuator of the aforementioned type wherein a rotatable mounting ring is provided between the wall member and the transducer means for permitting the wall member to rotate with respect to the transducer means and vice versa.

Another object of the present invention is to provide a transducer assembly of novel construction and design, the parts of which are arranged to provide a substantially small package.

Still another object of the present invention is to provide a simplified low cost structure of the aforementioned types having certain advantages contributing to efficiency, reliability, long life as well as to ease of maintenance.

Other objects and features of the invention will become apparent as the description proceeds, especially when taken in conjunction with the accompanying drawing(s), wherein:

FIGURE 1 is an elevational view, partly in section and with parts broken away.

FIGURE 2 is an elevational view of the transducer assembly.

FIGURE 3 is a vertical sectional view of the transducer assembly illustrated in FIGURE 2.

FIGURE 4 is an end view looking in the direction of arrows 4-4 of FIGURE 2.

FIGURE 5 is a vertical sectional view of another embodiment of the present invention.

FIGURE 6 is a schematic circuit diagram which utilizes a cylinder or actuator incorporating features of the present invention.

FIGURE 1 shows an electro-fluid actuator which consists of a cylinder 10 having a piston 12 and a tubular rod 14 movable therein. The cylinder 10 is honed to accurate size a 10-15 micro finish to provide long life and to minimize friction. The piston 12 is of one piece construction and has an O-ring seal 11 provided on the inside diameter against the rod 14. The piston 12 may be made from a high grade cast iron alloy. The tubular piston rod 14 is plated with hard chrome and is case hardened for protection. A pair of end caps 16 and 18 are provided at opposite ends of the cylinder 10 for closing the interior thereof. The end caps 16 and 18 are appropriately connected to the cylinder 10 by means of a plurality of threaded fasteners 19 which are received in aligned threaded openings provided in the end caps and cylinder.

End cap 18 has an annular stepped opening 20 provided therein for receiving a bushing 22 through which the rod 14 extends. The end caps 16 and 18 are provided with ports 26 and 28 respectively for supplying an actuating fluid to opposite ends of the cylinder 10. As an example, hydraulic fluid, compressed air or the like, may be utilized. In the present application reference will be made to the use of hydraulic fluid for effecting movement of the piston and rod assembly. The ports 26 and 28 are located in a closed hydraulic circuit 23 which includes a hydraulic servo valve 25 as best illustrated in FIGURE 6.

The end cap 16 is provided with a central opening 30 in which one end 32 of an elongated linear movement camming action stylus 34 is mounted. The stylus 34 is connected to a reinforcing plate 36 by means of a threaded fastener 38, as best illustrated in FIGURE 1. The other end of the stylus 34 is free and extends into the interior of the hollow piston rod 14. The stylus 34 is spaced from the interior wall of the rod 14. The stylus 34 has a longitudinal axis which is in substantial alignment with the longitudinal axis of the cylinder 10 and the piston and rod assembly. The stylus 34 is precision machined and ground to provide minute accuracy of readings as will subsequently appear.

The stylus 34, as best illustrated in FIGURES 1 and 2,

has an effective length equal to the length of the stroke of the piston and rod assembly. The transverse cross-sectional area of the stylus 34 throughout its effective length constantly decreases from end cap 16 to end cap 18. As illustrated, the stylus 34 is provided with eight sides, the essential feature being that one of the sides of the stylus 34 is tapered throughout the effective length of the stylus 34 to provide the constantly decreasing cross-sectional area as mentioned previously. The various sides of the stylus 34 are identified by the numerals 40, 42, 44, 46, 48, 50, 52, and 54. The upperside 40 is provided with a gradual taper or slope which starts near the end cap 16 and terminates at the free end of the stylus 34. The inclined sides 42 and 50 are substantially parallel as are inclined sides 46 and 54. This is indicated in FIGURE 4. In addition, the vertical sides 44 and 52 are also parallel to each other and to the longitudinal axis of the stylus 34. The remaining bottom or lower side 48 is substantially straight throughout the effective length of the stylus 34 and is parallel to the direction of movement of the piston and rod assembly.

In order to electrically reproduce the relative motion of the piston and rod assembly and the cylinder 10, a transducer assembly 60 is mounted on the same axis and integral or movable with the piston 12. By suitable means which will be subsequently explained the constant varying cross-sectional area of the stylus 34 or the effective depth of the stylus 34 is transmitted to the transducer 61 which forms a part of the transducer assembly 60 so that a proportionate output signal is generated for each increment of stroke of the piston 12 and rod 14.

The transducer assembly 60 also includes a tubular body 62 which surrounds the stylus 34 when in an assembled position. The transducer body 62 is provided at one end thereof with a radially extending flange 64 in which the transducer 61 is mounted. A housing plate 66 is bolted to the flange 64 by means of a plurality of threaded fasteners 68.

A rotatable mounting ring 70 rotates about a needle bearing 72 which is fixed to a piston rod retainer 74. The needle bearing 72, to which the transducer assembly 60 is connected, allows complete unlimited rotation of the piston 12 and piston rod 14 relative to the transducer assembly 60. The piston rod retainer 74 which is also tubular carries the needle bearing 72 on one end and is threaded to the piston rod 14 on the other end, as best illustrated in FIGURE 1. The piston rod retainer 74 provides means for holding the piston 12 against the shoulder 76 provided on the piston rod 14. The body 62 of the transducer assembly 60 is connected to the rotatable mounting ring 70 by a pair of shoulder screws 78, one of which is illustrated in FIGURE 3. A pair of closely wound springs 82 and 84 are associated with each of the screws 78 and are arranged concentric with the screws 78 so as to act against opposite sides of the housing plate 66. The shoulder screws 78 and associated springs provide a transducer assembly centering device which negates misalignment of the piston and rod assembly from being transferred to the centered transducer 61.

The body 62 of the transducer assembly 60 is provided with an oil impregnated bushing 90 through which the reactive core 92 extends. The reactive core 92 is made from a high grade steel and when in operation does not contact the transducer 61. The bushing 90 is effective to center the reactive core 92 through continuous cycling of the piston 12. The transducer 61, which is of the flat coil type, is completely adjustable for balancing out procedures. Transducer 61 may, as an example, take the form of a flat coil sensor Model Number D-152-H3 manufactured by the Bently Nevada Corporation, located at 100 Airport Road, Minden, Nevada. Complete environmental protection is provided by pressure potting and pressure compensation. The reactive core 92 and transducer 61 are arranged on the same axis which is sub-

stantially parallel to the longitudinal axis of the stylus 34. When the core 92 is moved in a manner to be subsequently explained, a proportional electrical energy change is effected in the transducer 61 because of the relative gap 93 between the core 92 and the transducer 61.

The body 62 is provided with two pairs of rotatable bearings 96 and 98. Each pair of guide bearings has the axes of the bearings lying in a plane which is substantially perpendicular to the longitudinal axis of the stylus 34. The rotatable guide bearing 96 and 98, as best illustrated in FIGURES 3 and 4, are adapted to bear against the straight sides 44 and 52 of the stylus 34. The guide bearings 96 and 98 help to center the transducer assembly 60 on the stylus 34 for maximum accuracy. The bearings 96 and 98 are rotatably carried by threaded bolts 99 or the like.

The body 62 is provided with a pair of actuating arms 100 and 102 which are pivoted to the body 62 by means of bolts 104 on opposite sides of the elongated stylus 34. The arms 100 and 102 have offset portions 106 which are adapted to carry a shaft 108. Mounted on the shaft 108 is a pair of roller bearings 110 and 112 which are adapted to engage the end 114 of the core 92. A spring 116 or other resilient means is provided between the body 62 and the core 92 for biasing the core 92 against the roller bearings 110 and 112.

A third roller bearing 118 is provided on the shaft 108 intermediate the pair of roller bearings 110 and 112 and is designed to ride along the tapered side 40 of the stylus 34. The spring 116 is effective to indirectly bias the third roller bearing 118 against the tapered side 40 of the stylus 34. The force which is induced indirectly by the spring 116 biasing the third roller 118 against the tapered side 40 of the stylus 34, is balanced by an additional pair of bearings 120 and 122 that contact the bottom straight side 48 of the stylus 34. The bearings 120 and 122 are rotatably carried by threaded bolts 124 and 126 respectively which are mounted on the body 62 and also held, along with roller 118, to center the transducer assembly 60 on the stylus 34 for maximum accuracy. The core 92 is undercut on its face as indicated at 130 so as not to engage the bearing 118.

The variable voltage signal or electrical energy change which is indicated by the transducer 61 is carried from the transducer 61 to a point outside of the cylinder 10 by a co-axial cable or output lead 130. The co-axial cable 130 is housed or contained within the interior of a coiled nylon tube or shroud 132. The inner end of the tube 132 is fixed to the transducer body 62 by a clamp 134. The coaxial cable 130 emerges from the shroud 132 adjacent the end cap 16 and leaves the cylinder 10 by means of a pressure-type connector 136 which is fixed to the end cap 16. The cable 130 is potted in a cavity 138 formed in the end cap 16, along with electronic circuitry. From the cavity 138 the cable 130 is directed through the electrical connector 140, which is a standard conduit type connection, to the various attendant electrical instrumentation that may be required such for an example, the volt meter 180 illustrated in FIGURE 6. The coiled nylon tube 132 acts as a protective shroud against wear and damage to the cable 130 as it extends and retracts within the cylinder 10 due to the movement of the piston and rod assembly.

A plurality of piston rings 142 are provided around the outer periphery of the piston 12 and are of the standard automotive type. Cylinder seals 144 are provided between the end caps 16 and 18 and the cylinder 10 so as to prevent fluid leakage from the cylinder 10. The seals 144 are leakproof and generally not affected by pressure surges because of the butt construction. A piston rod seal 146 is provided on the inner end of the bushing 22 and is provided with a lip for sealing at low pressures. In addition, a rod wiper seal 148 is provided on the outer end of the bushing 22 which prevents foreign particles or contaminants from entering the cylinder 10. The seal 148 is effective to wipe the rod 14 clean on its outstroke. 75

The bushing 22 provides accurate centering and side support for the piston rod 14. The bushing 22 is made of bronze and forms a cartridge which is designed for easy removal.

5 In operation, hydraulic fluid is directed into the interior of the cylinder 10 through the port 26 so as to move the piston 12 and the rod 14 which has the work connected thereto to the right. The piston 12 is stroked in opposite directions by a conventional servo valve 25 shown in FIGURE 6. As a result, the transducer assembly 60 is also moved to the right and thereby permits the bearing 118 to ride along the tapered side 40 of the stylus 34. The clamping action by bearing 118 and bearings 120 and 122 on the stylus 34 necessitates that the transducer assembly 60 follows the longitudinal axis of the stylus 34.

10 Due to the provision of the relative rotary movement between the transducer assembly 60 and the rotatable mounting ring 70 which is permitted by the gimbal action between the stud 78, springs 82 and 84 and plate 66, the transducer assembly 60 follows the axis of the stylus 34 while the housing plate 66 follows the axis of the piston 12. This is true even though the working axis of the stylus 34 and the working axis of the cylinder 10 may not always be the same axis due to manufacturing, assembly, unbalanced loading, or other uncontrollable factors.

15 As a result of the stroking of the piston 12 in opposite directions, the core 92 will travel back and forth through the bushing 90 as the transducer assembly 60 and piston 12 travels back and forth in the cylinder 10. The movement of the core 92 is due to the fact that the bearing 118 rides up or down along the tapered side 40 of the stylus 34. The movement of the core 92, which is on the same axis as the transducer 61, is effective to vary the gap 93 between the core 92 and transducer 61. As the core 92 is moved closer or further away from the transducer 61, a proportional electrical energy change, such as a change in voltage, is effected. The electrical output signal which is emitted by the transducer 61 is proportional to an increment of stroke of the piston 12. The electrical output signal is properly amplified and de-lineated through and out of the cylinder 10 by means of the cable or lead 130. The signal thus generated is available to perform any task or readout that may be required.

20 FIGURE 5 shows another embodiment of the present invention wherein a linear variable differential transducer (L.V.D.T.) 156 is carried by the body 158 of the transducer assembly 160 in place of the flat coil transducer 61 illustrated in FIGURE 1. Transducer 156, as an example, may take the form of the L.V.D.T. Model No. 350ES-L manufactured by the Schaevitz Engineering, Box 505, Camden, New Jersey. The main core 162 is movable in an oil impregnated bushing 164 as in the other embodiment and carries a shaft 166 which in turn carries the transducer core 168. The movement of the main core 162 is the same as in the other embodiment. The relative motion of the transducer core 168 within 25 the linear variable differential transducer 156, which is energized, induces a variable voltage output or electrical energy change which is proportional to the relative position of the transducer core 168. The movement of the main core 162 is dependent on the position of the roller bearing 170 on the tapered side 40 of the stylus 34 as in the other embodiment.

25 The present invention is designed to emit an electrical signal that varies proportionally to the effective length of the tapered side of the stylus. The transducer assembly centering device is effective to compensate for misalignment, as an example up to $\frac{1}{32}$ ", between the axis of the transducer assembly 60 and the axis of the stylus 34. The rotation of the piston 12 and rod 14 with respect to the cylinder 10 will not rotate the transducer assembly 60 and such rotation does not effect the output

from the transducer 61. The pressure of the spring 116 keeps the roller 118 on the tapered side 40 of the stylus 34. It should be understood that the slope of the stylus 34 can be changed to suit any particular design or problem.

The present invention is characterized by its inherent versatility which makes it suitable for automation. As an example, the circuit illustrated in FIGURE 6 may be constructed and arranged whereby the rod 14 of the hydraulic cylinder or actuator 10 is connected to a paint gun utilized in an automation system. Consider the manner and varied operations required to paint the hood of an automobile. The paint gun, not shown, is placed under the control of the piston and rod assembly. Movement of the piston and rod assembly moves the paint gun a corresponding distance. The movement of the piston and rod assembly is recorded by feeding the output signal from the co-axial cable 130 to a tape recorder 171 which makes a permanent record on tape of the various movement required to paint the hood. When the tape recorder 171 is recording the piston and rod assembly is manually moved in the cylinder 10 without the use of any hydraulics from the closed hydraulic circuit 23. The linear displacement or stroke of the piston 12 and rod 14 is transmitted to the transducer assembly 60 as mentioned previously whereby a proportional output signal is generated for each increment of stroke of the piston 12 and rod 14 which in turn is recorded on the tape. The final result is that a tape is produced which accurately records the plurality of movements required to paint the hood and which may subsequently be utilized to automatically paint other automobile hoods.

When it is desirable to utilize the recorded sensing tape from the tape recorder 171 to paint other automobile hoods, the tape, which provides a command signal on playback, is fed into the function generator 172. The command signal from the generator 172 is directed across the amplifier device 174 which includes a summing device 176 and an amplifier 178. The command signal on the output side of the amplifier 178 is directed to the hydraulic servo-valve 25 which is in turn incorporated with the hydraulic cylinder 10 in the closed hydraulic circuit 23. The command signal controls the flow of hydraulic fluid from one cylinder port 26 to the other port 28. The electrical energy input is transformed into the mechanical energy output of the piston and rod assembly which directs the painting action. When the cylinder 10 is under the direction of the tape, the electro-mechanical transducer assembly 60 serves the important function of reading and comparing the position of the piston 12 and rod 14 with the master tape. The DC voltage signal or output generated by the transducer assembly 60 is fed through the co-axial cable 130 to the summing device 176 of the amplifier device 174. Any difference or error between the command signal and the output signal of the transducer assembly 60 in turn produce a correcting signal for the servo-valve 25 which in turn directs fluid to the particular port so as to move the piston and rod assembly to the exact place it should be in the cylinder 10 as determined by the command signal on the tape.

A voltage meter 180 is connected to the co-axial cable 130 whereby the voltage from the transducer assembly 60 can be read direct. This voltage is proportionate to the increment of stroke of the piston and rod assembly.

The drawings and the foregoing specification constitute a description of the improved electrohydraulic actuator in such full, clear, concise and exact terms as to enable any person skilled in the art to practice the invention, the scope of which is indicated by the appended claims.

What I claim as my invention is:

1. An actuator comprising a tubular housing member, a wall member in said housing member, a linear movement camming action stylus in said housing mem-

ber and fixedly mounted with respect to one of said members, and electro-mechanical transducer means carried by the other of said members and including movable follower means in contact with said stylus, said transducer means being effective to convert the relative displacement between said members as indicated by the movement of said follower means into an equivalent electrical energy change.

2. The actuator defined in claim 1 wherein said housing member and said wall members are in the form of a cylinder and piston respectively.

3. The actuator defined in claim 1 wherein said stylus is fixed to said housing member and said transducer means is carried by said wall member.

4. The actuator defined in claim 3 wherein said stylus and said housing member are elongated and said stylus has substantially the same longitudinal axis as said housing member.

5. The actuator defined in claim 3 wherein said stylus is elongated and said electro-mechanical transducer means has substantially the same axis as said stylus.

6. The actuator defined in claim 3 wherein means are provided for aligning the axis of said electro-mechanical transducer means with the longitudinal axis of said stylus.

7. The actuator defined in claim 1 wherein the side of said stylus in contact with said movable follower means is tapered.

8. The actuator defined in claim 7 wherein the length of the taper on said stylus is substantially equal to the maximum linear displacement between said wall member and said housing member.

9. The actuator defined in claim 1 wherein means are provided for connecting opposite sides of said wall member to a source of actuating fluid.

10. The actuator defined in claim 3 wherein means are provided between said wall member and said transducer means for permitting relative rotation between said wall member and said transducer means.

11. An actuator comprising a tubular housing, a movable wall in said housing, a stylus fixedly mounted in said housing, one side of said stylus being tapered, and an electro-mechanical transducer assembly connected to said wall for movement therewith, said transducer assembly including a transducer and follower means, said follower means being in contact with the tapered side of said stylus for transmitting to said transducer a mechanical input signal which is dependent on the position of said follower means on the tapered side of said stylus as determined by the movement of said wall, said transducer being effective to generate an electrical output signal which is proportionate to the aforesaid mechanical input signal.

12. An actuator comprising a tubular housing, a movable wall in said housing, an elongated stylus fixedly mounted in said housing, one side of said stylus being tapered, an electro-mechanical transducer assembly having a longitudinal axis and connected to said wall for movement therewith, said transducer assembly including a transducer and follower means, said follower means being in contact with the tapered side of said stylus for transmitting to said transducer a mechanical input signal which is dependent on the position of said follower means on the tapered side of said stylus as determined by the movement of said wall, said transducer being effective to generate an electrical output signal which is proportionate to the aforesaid mechanical input signal, and means for maintaining the longitudinal axis of said transducer assembly in substantial alignment with the axis of said stylus.

13. An actuator comprising a tubular housing having a longitudinal axis, a movable wall spanning the interior of said housing and having substantially the same axis as said housing, an elongated stylus fixedly mounted in said housing and having substantially the same longitudinal axis as said housing and wall, one side of said stylus being tapered, an electro-mechanical transducer as-

sembly having a longitudinal axis connected to said wall for movement therewith, said transducer assembly including a transducer and follower means, said follower means being in contact with the tapered side of said stylus for transmitting to said transducer a mechanical input signal which is dependent on the position of said follower means on the tapered side of said stylus as determined by the movement of said wall, said transducer being effective to generate an electrical output signal which is proportionate to the aforesaid mechanical input signal, and means for maintaining the axis of said transducer assembly in substantial alignment with the axis of said stylus.

14. The actuator defined in claim 13 wherein said movable wall is in the form of a piston and rod assembly.

15. The actuator defined in claim 14 wherein one end of said stylus is fixed to an end wall of said cylinder and the other end is free.

16. The actuator defined in claim 15 wherein said piston and rod assembly is tubular and said other end of 20 the stylus is received within the interior of said piston and rod assembly.

17. A transducer assembly comprising a tubular body having a longitudinally extending axis, a transducer carried by said body, a movable core having one end opposite said transducer, said core and said transducer having an axis which is substantially parallel to the longitudinal axis of said body, an actuating arm pivoted to said body about an axis extending transversely to the longitudinal axis of said body, and a roller bearing carried by said 25 30

arm in contact with the other end of said core, said roller bearing being effective to move said core with respect to said transducer in response to the movement of said arm to produce a change in the electrical energy output of the transducer.

18. The transducer assembly defined in claim 17 wherein resilient means are provided between said body and said core for biasing said core against said bearing.

19. The transducer assembly defined in claim 17 wherein a pair of actuating arms are provided, said arms being connected by a shaft, and a pair of roller bearings carried by said shaft and in contact with said other end of said core.

20. The transducer assembly defined in claim 19 wherein in a third roller bearing is carried by said shaft intermediate the other of said roller bearings, said third roller being spaced from said other end of said core.
